UNITED STATES PATENT OFFICE.

HENRY W. CORNING, OF CLEVELAND, OHIO.

DROPHEAD CABINET FOR SEWING AND OTHER MACHINES.

Application filed February 16, 1922. Serial No. 536,949.

To all whom it may concern:

Be it known that I, HENRY W. CORNING, a citizen of the United States, residing at Cleveland, in the county of Cuyahoga and State of Ohio, have invented certain new and useful Improvements in Drophead Cabinets for Sewing and Other Machines; and I do hereby declare the following to be a full, clear, and exact description of the invention, such as will enable others skilled in the art to which it appertains to make and use the same.

My invention relates to that class of drop-head cabinets in which the machine-supporting bed is raised and lowered by means of a swinging leaf hinged to the top of the cabinet and operatively connected with the supporting bed through means including a cable. In cabinets of this class, when the bed is raised to bring the supported machine to working or operative position above the top of the cabinet, it is desirable that the bed should always be brought to a predetermined position substantially flush with the top or table of the cabinet. To do this it is necessary that some provision be made to take up or control the slack in the connecting cable between the bed and the operating table leaf, and it has been the object of my present invention to provide a simple and efficient means for controlling the slack in such cable. This object I attain by the novel means illustrated in the accompanying drawings forming part of this specification, in which—

Figure 1 is a fragmentary view of a sewing machine cabinet, partly in section, showing a machine supporting bed hinged to the cabinet table, a swinging leaf hinged to one end of said table, a cable between said bed and leaf, and a device embodying my invention secured to the bed for coupling one end of the cable thereto and having means for taking up slack in the cable.

Fig. 2 is an enlarged side elevation, partly in section, of the cable coupling and adjusting device detached from the machine supporting bed.

Fig. 3 is an end view of the same, showing the lower end of the cable connected therewith as in Fig. 2, and

Fig. 4 is a top plan view of the same.

Similar reference characters indicate like parts in the several figures of the drawings.

My invention may be applied to any type of cabinet or stand having a machine-sup-

porting bed which is adapted to be operated through the instrumentality of a cable to lower the machine into the cabinet when not in use and to raise the machine above the cabinet top or table when desired for use, the invention, as heretofore indicated, being directed particularly to means for taking up slack in the cable resulting from undue stretching of the same, whereby the bed may be always brought to the same predetermined position when raised.

In the drawings, which show only so much of a sewing machine drop-head cabinet as is necessary to illustrate my invention, 2 indicates the top or table of the cabinet having an opening 3 for the passage of the machine in being raised and lowered to and from its operative or working position; 4, the machine-supporting bed pivoted at one edge to the table within its said opening 3, as at 5; 6, a part of the frame of a sewing machine mounted on said bed; and 7, a swinging leaf hinged to the table at 8 and being movable from a closed position over the opening in the table when the machine is lowered, to an open position extending beyond one end of the cabinet when the machine is raised, this leaf operating through suitable connections, upon its opening and closing movements, to raise and lower the bed and the machine supported thereon. These several parts as thus far described are of substantially usual construction and operation.

The bed 4, as here shown, has a cleat 9 at its under side which projects beyond the rear edge thereof to form a stop-shoulder 10 for engagement with the under side of the table when the bed is brought to a raised position, as shown by dotted lines in Fig. 1.

In the present case, the operating connection between the leaf and bed comprises a cable 11 having coupling eyes 12, 12, at its opposite ends, one of which is connected with the leaf by suitable fastening means, such as the screw 13, and the other of which is connected with the rear edge of the bed 4 through the medium of my improved coupling and adjusting device, the cable between its ends passing through a guide opening 14 in the cabinet, as shown in Fig. 1.

My improved cable coupling and adjusting device comprises a bracket 15 attached to the under side of the bed 4 by suitable fastening means, such as the screws 16, and

having a depending arm 17 provided with an opening 18 in which a lever 19 is loosely seated for pivotal connection with the bracket. This lever 19 is here shown as 5 formed at its rear end with a hook 20 for detachable connection with the coupling eye 12 in the end of the cable 11, and at its opposite or front end as bearing against an adjustable support, here shown in the form of 10 a nut 21 having a screw-threaded connection with a pin 22 depending from and rigidly attached to the bracket 15. By screwing the nut 21 upwardly on the pin 22 it will operate to raise the engaging end of 15 the lever and cause the latter to rock on its bearing at the upper end of the opening 18 in the bracket and thereby lower its rear or hook end, which movement of the latter will act to shorten the cable between the leaf 20 and bed whereby the latter may always be caused to be brought to a raised position with its stop-shoulder 10 in contact with the under side of the table.

As a means for holding the lever 19 in its 25 operative connection with the bracket 15, that is, in position in the opening 18, and also with its front end bearing on the adjustable support 21, it is engaged at its front end by the pin 22 which extends loosely 30 through an opening 23 therein as shown.

The lever 19 is here shown as resting on the washer 21 adjacent to one edge thereof, whereby it will have a tendency to cant 35 said washer and cause it to bind against the threads of the pin 22, in this way acting to lock the washer in its adjusted position.

The cable coupling and adjusting device herein shown and described is of cheap and simple construction, and has been found to 40 be most efficient for the purposes intended.

What I claim is:

1. In a drop-head cabinet, the combination with the table, a movable leaf, a vertically movable machine-supporting bed, and a cable operatively connecting the leaf and 45 bed whereby the opening and closing of the leaf will effect a raising and lowering of the bed, of a bracket attached to the bed having a depending arm provided with an opening therein, a lever loosely seated in 50 said opening and having a rear hook-shaped end for detachable connection with the lower end of the cable and also having an opening at its front end, a threaded pin carried by the bracket loosely engaging the 55 lever through the said opening at its front end, and a nut threaded on said pin providing an adjustable support for the front end of the lever, for the purpose set forth.

2. In a drop-head cabinet, the combination with the table, a movable leaf, a vertically movable machine-supporting bed, and a cable operatively connecting the leaf and 60 bed whereby the opening and closing of the leaf will effect a raising and lowering of the bed, of a bracket attached to the bed having a depending arm provided with an opening therein, a lever loosely seated and pivoting in said opening and having its rear end in connection with the cable and its 65 front end provided with an opening, a threaded pin also carried by the bracket and extending through the opening at the front end of the lever and holding the latter against end-wise movement in the bracket 70 opening, and a nut threaded on said pin engaging at one edge thereof with the front end of the lever and providing an adjustable support therefor.

HENRY W. CORNING.
